UNITED STATES PATENT OFFICE.

HENRY H. TAYLOR, OF BRIDGEPORT, CONNECTICUT.

DESIGN FOR A WAIST-EXTENDER.

SPECIFICATION forming part of Design No. 34,875, dated July 30, 1901.

Application filed June 21, 1901. Serial No. 65,511. Term of patent 7 years.

To all whom it may concern:

Be it known that I, HENRY H. TAYLOR, a citizen of the United States, residing at Bridgeport, in the county of Fairfield and State of Connecticut, have invented and produced a new and original Design for a Waist-Extender for Ladies' Wear; and I do hereby declare the following to be a full, clear, and exact description of the invention, such as will enable others skilled in the art to which it appertains to make and use the same.

Referring to the accompanying drawings, Figure 1 is a front elevation of my design, and Fig. 2 a central vertical section at the line $\alpha\alpha$ of Fig. 1.

Similar numbers of reference denote like parts in both figures of the drawings.

The leading or material features of my design consist of the two lateral stay-strips 1 2, whose inner extremities approach each other at an angle, and the vertical stay-strip 3, which is secured to the strips 1 2 at their point of junction and which extends both above and below said strips, the lateral strips 1 2 adapted at their outer extremities for attachment with any suitable belt and buckle, (not shown,) while the vertical strip 3 is provided in its upper portion with keyhole-slots 4 and at its lower end with a downwardly-opening hook 5.

Having thus described my invention, what I claim as new, and desire to secure by Letters Patent, is—

The design for a waist-extender for ladies' wear, as herein shown and described.

In testimony whereof I affix my signature in presence of two witnesses.

HENRY H. TAYLOR.
